UNITED STATES PATENT OFFICE.

FRANK W. MERRICK, OF BOSTON, MASSACHUSETTS.

FILLER FOR SHOE-BOTTOMS.

1,203,229.

Specification of Letters Patent. Patented Oct. 31, 1916.

Application filed April 28, 1914. Serial No. 834,922.

To all whom it may concern:

Be it known that I, FRANK W. MERRICK, a citizen of the United States, residing at Boston, in the county of Suffolk, State of 5 Massachusetts, have invented a certain new and useful Improvement in Fillers for Shoe-Bottoms, of which the following is a specification, reference being had therein to the accompanying drawings.

10 My invention consists in a novel and improved composition of matter more especially adapted for use in the manufacture of boots and shoes as a filler or filling in the space or hollow between the insole and the 15 outsole of a shoe, but also applicable for use in various other connections.

The general objects of the invention are mainly to provide a filler for shoe bottoms which shall be free from serious drawbacks 20 and disadvantages of the shoe-bottom fillers at present in use, and which shall possess several important and desirable advantages. Among the said objects are to provide a 25 filler material having, as prepared, the plasticity which is required in order to enable it to be spread out upon the insole of a shoe and caused to fill the required space and all inequalities. Also, one which shall become firm and dry with moderate rapidity. 30 Also, one that shall possess flexibility and durability, and also waterproof qualities. Also, one which shall be free from liability to give way and become displaced as a result of becoming softened by warmth during 35 use and by the pressure of the parts of the foot of the wearer. A really satisfactory shoe bottom filler possessing the desired characteristics has not been procurable in the market.

40 The drawing shows in longitudinal vertical section a shoe with a filler applied. The upper is marked 1, 2 is an insole, 3 a welt and 4 an outsole. The projecting margins of the upper, insole and welt are secured 45 together by the stitches of the inseam, and trimmed off close to the inseam. The filler 5 occupies the space or hollow inclosed by the closely-trimmed projecting margins, between the insole and the outsole.

50 My invention consists in a plastic composition comprising essentially a solution of pyroxylin, a suitable base consisting pref-

erably of ground cork, and asbestos fiber or other fibrous material. The solution of pyroxylin serves as a binder or cement and 55 gives certain important properties or qualities rendering the composition particularly useful as a filler for the bottoms of shoes as aforesaid. Other elastic material than cork may be employed as the base, as for instance 60 finely divided wood, leather, paper-pulp, etc. The composition while still in a plastic state may be applied and spread readily without the application of heat. It will fill perfectly the cavity or recess at the surface of 65 the insole of a shoe. It hardens in place with comparative promptness. It is highly adhesive. It remains very flexible. It is perfectly waterproof. The fibrous matter keeps the layer of composition from 70 altering its position under the pressure of the weight of the wearer of the shoe, transmitted by different portions of the underside of his foot to the insole and through the latter to the sheet of filler. It thus 75 remedies a serious defect or drawback that is incident to bottom fillings composed of certain 80 filler material at present extensively in use. The latter material manifests a tendency to soften up under the influence of the warmth 85 and pressure of the wearer's foot, so that at those places where the pressure is greatest the filler is squeezed out horizontally in different directions. For instance, the pressure applied by the ball of the wearer's foot 90 causes any filler that is affected by moisture or heat to flow forward under the toes of the foot, thereby producing discomfort. A filler made of my composition, not only is unaffected by moisture or heat, but has no 95 tendency whatever to change its position or flow as just explained under pressure.

What I claim is—

The improved plastic adhesive composition of matter for use as a filler for shoe bottoms comprising an admixture of pyroxylin in solution, cork in a finely divided state, and sub-divided fibrous material. 95

In testimony whereof I affix my signature in presence of two witnesses.

FRANK W. MERRICK.
